AIR HEATING APPARATUS

William S. Somers, Columbus, Ohio

Application June 22, 1937, Serial No. 149,609

7 Claims. (Cl. 126—114)

This invention relates to improvements in air heating systems, particularly systems of the forced circulation type, such as those employed for the heating of residences and other buildings.

In warm air heating and conditioning systems, considerable difficulty is often encountered in the installation of ducts employed in conveying air to and from the air heater or conditioner to different rooms of a residence or building. This is often due to the placing of the furnace or other air conditioner in the corners or near the walls of a furnace room or in other relatively inaccessible locations or to the architectural features of the building itself. In most instances, it is desirable to place the furnace casing in such position that it will not occupy a prominent position in a residence basement or furnace room. Again, many furnace casings are so constructed that the ducts for conveying heated air to the building rooms are connected with the top of the furnace casing, while the cold air or return ducts enter such furnace casings near the bottom portions thereof. These conditions, among others, militate against facility, simplicity and economy in the installation of air heating or conditioning systems wherein associated duct work is used, rendering such systems costly and difficult to install and frequently acting as a hindrance in obtaining thermal efficiencies.

The present invention aims to alleviate these conditions to a very substantial degree and, accordingly, utilizes a warm air furnace casing divided internally into an outer return air chamber and an inner heated air chamber. These chambers are so disposed that both the return air and the outgoing heated air enter and leave the furnace casing by way of a plenum housing of novel design formed with the top of the furnace casing. This housing is constructed to include warm air and return air compartments disposed preferably in the same horizontal plane, the said compartments being spaced from each other and communicate respectively with the return air and warm air chambers of the furnace casing. Air conveying ducts enter the housing through the outer side walls only thereof and are disposed in open communication with the housing compartments, the construction of the furnace casing and housing being such as to enable the ducts to occupy the most advantageous operating positions, avoiding crossing or intersecting duct work and making for adequate head room or clearance in furnace rooms of ordinary height.

An object of the invention resides in providing a heater of the type under consideration with an adjustable plenum housing on the top of the furnace casing to which the warm air supply and return air ducts are connected, the said plenum housing being provided with a pair of spaced compartments, one of said compartments being connected with the warm air supply ducts and in open communication with the inner air heating chamber of the furnace, while the other of said compartments is connected with the return air ducts and is in open communication with the outer chamber of the furnace casing, the said plenum housing serving to provide for distribution of air to the furnace chambers and for convenience and orderliness in placing the related ducts in their most advantageous operating positions.

It is a further object of the present invention to provide an improved heating system involving a casing construction which will be more economical to manufacture and install than analogous prior types of casings, will require less floor space for comparable heating capacities, and will enable the heat developed by the operation of the system to be utilized with greater effectiveness.

For a further and more detailed understanding of the invention, reference is to be had to the following description and the several forms of the present invention selected for illustration in the accompanying drawings.

In said drawings:

Fig. 1 is a perspective view of the exterior of a furnace casing and the plenum housing used in connection with the heating system comprising the present invention;

Fig. 2 is a vertical sectional view taken through the casing and disclosing more particularly its internal construction;

Fig. 3 is a transverse horizontal sectional view taken through the casing on the plane disclosed by the line III—III of Fig. 2;

Fig. 4 is a similar view taken through the plenum housing on the plane indicated by the line IV—IV of Fig. 2;

Fig. 5 is a diagrammatic view showing a modified type of plenum housing in which the warm air outlets are disposed in a plane above the return air inlets;

Fig. 6 is a view similar to Fig. 5 disclosing another variation of the plenum construction wherein the warm air outlets are arranged below the plane of the return air inlet or inlets;

Figs. 7 and 8 are horizontal sectional views

taken respectively on line VII—VII and VIII—VIII of Figs. 5 and 6.

Referring more particularly to the drawings and to the form of my improved heating system set forth in Figs. 1 to 4 inclusive thereof, the said system, designated in its entirety by the letter A, comprises a substantially cylindrical outer casing 1 of sheet metal and an inner concentrically arranged casing 2 of similar construction. The cylindrical formation of the casing is preferred because of simplicity and economy in its manufacture. The lower edges of the casing may rest on a base plate 3 disposed on a floor or other similar support. The spacing of the casings 1 and 2 provides therebetween an annular cold air outer chamber 4, while within the casing 2, the latter provides an inner warm air heating chamber 5.

At one side, the outer casing 1 is formed to include an enlargement 6 within which there is arranged a fan or blower 7 driven by an electric motor 8, the fan or blower being so disposed as to draw air from the outer chamber 4 and deliver the same under positive pressure for forced flow upwardly through the inner heating chamber 5. Arranged within the enlargement 6 of the outer casing is a filter 9 of either the porous or spray type, by which fine solid particles are removed from the air drawn into the furnace casing prior to the passage thereof through the fan or blower. It will be noted that the filter herein specifically shown, in lieu of being placed horizontally, as is customary, is arranged at an acute angle to the vertical, to render as small as possible the floor dimensions of the lateral casing enlargement 6 and yet to provide a filter having the required number of square feet of surface area to obtain full and efficient operation. One or more of the sides of the enlargement 6 may be provided with a door affording convenient access to the fan or blower and the filter arranged above the same.

Within the inner chamber 5, there is arranged any suitable type of heating element of the character indicated at 10. In the form illustrated, this element comprises a vertical drum 11 preferably composed of riveted and welded boiler plate material. Any of the standard types of fuel may be burned in the bottom of the heating element, and to this end the drum is provided at its lower end with a horizontally extending branch 12 preferably adapted for the reception of an automatic oil, coal or gas burner of any conventional design. Above the branch 12, the drum is connected with a corresponding horizontally extending boxing 13, the open forward end of which is normally covered by an access door 14. The circumference of the outer casing is such that the heating element extensions 12 and 13 are enclosed by the outer casing, as shown more particularly in Fig. 3, and the said extensions 12 and 13 are readily accessible by means of a hinged door 15, forming a symmetrical part of the outer wall construction of the casing 1.

In the operation of the fan or blower, air is drawn generally downwardly through the outer chamber 4 as a result of negative or minus pressures established within the chamber 4 by the operation of the fan or blower. This fact permits of economical construction on the part of the outer casing since by this method of air flow, it is not necessary as in previous designs to produce an air-tight, insulated, rigidly constructed, welded casing. Any air that might seep through the joints of the casing 1 from the atmosphere is

merely introduced into the air undergoing heating, filtration or circulation in the entire heating system and does not in any way detrimentally affect the operation of the latter. Also the relatively cool air passing through the chamber 4 keeps the walls of the casing 1 comparatively cool so that enamel or other decorative finishes applied to the outer surface of the casing 1 will not be injured by the internal heat of the furnace; the construction minimizing heat losses to the atmosphere and eliminating the necessity for employing insulated walls.

The return air introduced into the outer chamber passes through the filter 9 where foreign particles composed of small solids are removed and the filtered air delivered to the suction side of the fan or blower, the air being filtered after passing through the outer chamber and over exposed heating surfaces therein. The fan then operates to force the air under pressure into the inner chamber 5 causing its positive movement through that chamber. During the passage of the filtered air through the inner chamber, the air contacts with the heated surfaces of the heating element 10 or has the temperature thereof raised by heat radiated or otherwise delivered from the outer surfaces of the element 10. The surface area of the heating element is increased as usual by connecting the upper end of the drum 11 with a hollow secondary heating section 16, which is disposed in the back of the chamber 5 and has the bottom thereof connected with a stack or flue outlet.

The heated gases of combustion, developed by the burning of fuel in the lower part of the drum 11, pass upwardly through said drum, heating the steel plate walls of the latter. The gases are then passed through a horizontal extension at the top of the drum and are directed downwardly through the secondary heating section 16 and thence to a stack or chimney outlet. The heating element thus provides sufficient heat releasing surface to impart the required temperature to the air passing upwardly under positive pressures through the inner chamber 5. The inner casing 2 may also be of economical construction since the escape of heated air through any joints that may exist therein merely results in the introduction of the escaped air into the outer chamber 4 and its recirculation through the fan or blower.

In prior types of furnaces, air seeping through the casing of the furnace is delivered to the atmosphere of the furnace room and its heating effect lost. This is one of the reasons for the heavy, expensive and air-tight cabinet construction in prior types of furnaces.

An important feature of the present invention resides in providing the top of the furnace with an improved plenum housing 17 which is adjustable, insofar as its operating positions are concerned, for simplifying the arrangement of air conveying ducts, in adapting the furnace to the physical limitations of furnace rooms of varying design and effecting desired flow of air into or from the furnace chambers.

The plenum housing comprises inner and outer sections, preferably of sheet metal walls or walls of composition materials having sound absorbing properties, which are formed to produce a substantially L-shaped return air compartment 18 and a substantially square plenum compartment 19. The compartment 19 is formed with an L-shaped bottom 20, forming a rectangular opening 21 in the bottom of the plenum compartment 7

which is in open communication with the top of the inner air heating chamber 5, so that the heated air arising from the chamber 5 readily enters the compartment 19 and may then be distributed 5 to the various rooms of a house or building by way of ducts 22 which extend from two sides of the housing. The return air compartment 18 is provided with an open bottom, the open area of which may be varied as desired so that it is in 10 direct communication with the outer chamber 4 so that the cool return air of the heating system may enter the compartment 18 through one or more ducts 23 and then be delivered to the chamber 4 to obtain uniform or required flow there- 15 through.

The inner and outer sections of the plenum housing preferably include frusto-conical skirts, as indicated at 24, which terminate in vertical 20 annular flanges 25, the latter being received within correspondingly formed grooves provided 25 in the upper edges of the casings 1 and 2. This construction enables the plenum housing to be mounted on the top of the furnace casing in any desired position of rotation with respect to 30 the vertical axis of the casing so that the ducts 22 and 23 may be located to the best advantage when the physical restrictions of a furnace room are taken into consideration. Often a furnace is required to be situated in a corner of a furnace 35 room where adjacent walls or other supporting members interfere with normal duct arrangements. With the plenum housing constructed as disclosed in the drawings, such conditions can be most successfully met by adjusting the operating 40 position of the plenum housing on the casing so that but minimum interference will exist in the extension of the ducts to vertical risers or other leaders and ample area provided for duct attachment.

45 In the plenum housing disclosed in Figs. 1, 2 and 4, the ducts 22 and 23 are arranged substantially in the same horizontal plane. This arrangement, however, may be varied as disclosed in Fig. 5, when the compartment 19a of the plenum housing is arranged in a plane above 50 the compartment 18a for the return air, thus enabling the warm air ducts 22a to be disposed in a horizontal plane above that of the return ducts 23a. The reverse of this arrangement is disclosed in Fig. 6, wherein the plenum compartment 19b is arranged in a horizontal plane below that of the return air compartment 18b, with the result that 55 the return air duct or ducts 23b are arranged in a horizontal plane above that of the warm air ducts 22b. It will be obvious to those skilled in the art that other variations may be provided in the matter of drawing air into and expelling the same from the plenum housing. While the plenum housing has been shown as substantially 60 rectangular when viewed in plan, it is of course within the scope of the invention to make the same cylindrical, or substantially so, if such construction should be desired.

In view of the foregoing, it will be seen that 65 the present invention provides a heating system so constructed that no outward pressure obtains on the outer walls of the enclosure, thereby avoiding pressure leaks and heat losses. The outer chamber of the casing, through which the return 70 air passes, absorbs heat from the walls of the inner casing, thus reducing the usual heat losses from the casing to the atmosphere of a furnace room. Said outer chamber maintains the walls of the outer casing at a low temperature, so that 75 such walls may be attractively finished, as desired,

with various types of coating materials and deterioration of such coating materials avoided as a result of furnace heat.

Again, no insulation is required, as in previous types of cabinets, to maintain low casing or cabinet temperatures since heat obtained from the walls of the inner casing is efficiently transferred to the return air causing the latter to be pre-heated and thereby efficiently used in the furnace. 10

The construction readily permits of the use of high heating unit temperatures, enabling heat resisting alloys to be used advantageously in the walls of the heating element and at the same time to obtain compactness in design for a given 15 thermal output. The construction is conveniently adaptable to the installation of automatic controls and accessories in the outer casing and, due to lower temperature, insures better functioning of such controls and accessories. The inclined 20 filter permits of the exposure of ample filter area to the air stream and yet compactness in design obtained. The system is adaptable to all existing 25 types of combustion devices without necessitating any change in their construction. By its simplicity of design, the casing set forth insures low cost units which perform even more effectually and efficiently than comparable capacity furnaces of present day manufacture. The blower unit 30 may be formed as a part of the casing, as disclosed, or may be a separate unit.

The plenum housing provides adjustable warm 35 and cold air chambers to which all ducts can be connected at ceiling height. The adjustability in position of the chambers provides for simplifying duct connections, due to the fact that crossing ducts may be eliminated; also the points of connection for either warm or cold air ducts 40 may be readily varied to meet actual installation conditions. By combining the warm air and cold air plenum chambers in one housing, temperature losses from the walls of the warm air chamber are eliminated by the absorption of heat by air passing through the return air chamber. 45 Due to this heat transfer through the juxtaposition of the plenum chambers, the walls of the plenum housing are maintained at low temperatures so that low cost finishes may be applied to exterior surfaces. 50

What is claimed is:

1. In an air heater, a casing divided internally into inner and outer chambers communicating at their lower ends, a second casing supported on the upper end of said first casing, a vertical partition wall joining the side walls of said second casing and dividing said second casing into inlet and outlet compartments, one of said compartments communicating with the inner chamber and the other compartment communicating with the outer chamber of said first casing, air inlet and outlet openings communicating through the side walls of the second casing with the respective inlet and outlet compartments, said second casing being adjustable on said first casing whereby 60 to position said openings. 65

2. The structure set forth in claim 1 in which the second casing is quadrangular prismatic in shape and the vertical partition wall is L-shaped in horizontal cross-section. 70

3. In an air heater, a casing divided internally into inner and outer chambers communicating at their lower ends, a second casing supported on the upper end of said first casing, and a vertical partition wall joining the side walls of said second 75

- casing and dividing said second casing into inlet and outlet compartments, one of said compartments communicating with the inner chamber and the other compartment communicating with the outer chamber of said first casing, air inlet and outlet openings communicating through the side walls of the second casing with the respective inlet and outlet compartments.
4. In an air heater of the type having a casing divided internally into inner and outer chambers communicating only at their lower ends, a second casing provided at the upper end of the first casing, said second casing being separable from and adjustable with respect to said first casing, the side walls of the second casing having portions inwardly offset with respect to the side walls of the first casing, and partition means dividing said second casing into a pair of adjoining compartments, one of said compartments communicating with the inner chamber of said first casing and the other compartment communicating with the outer chamber, each compartment having an exterior wall formed by a portion of the walls of said second casing, an exterior wall of each compartment having an opening through which communication between the compartments and air conductors is established.
5. In an air heater of the type having a casing divided internally into inner and outer chambers communicating only at their lower ends, a second casing having vertical side walls provided at the upper end of the first casing, the side walls of the second casing having portions inwardly offset with respect to the side walls of the first casing, said second casing being separable from and adjustable with respect to said first casing, and a vertical partition wall dividing said second casing into a pair of adjoining compartments, one of said compartments communicating with the inner chamber of said first casing and the other compartment communicating with the outer chamber, each compartment having an exterior wall formed by a portion of the walls of said second casing, an exterior wall of each compartment having an opening through which communication between the compartments and air conductors is established.

ment having an opening through which communication between the compartments and air conductors is established.

6. In an air heater of the type having a casing divided internally into inner and outer chambers communicating only at their lower ends, a second casing provided at the upper end of the first casing, said second casing being separable from and adjustable with respect to said first casing, the side walls of the second casing having portions inwardly offset with respect to the side walls of the first casing, and a horizontal partition wall dividing said second casing into a pair of adjoining compartments, one of said compartments communicating with the inner chamber of said first casing and the other compartment communicating with the outer chamber, each compartment having an exterior wall formed by a portion of the walls of said second casing, an exterior wall of each compartment having an opening through which communication between the compartment and an air conductor is established.

7. In an air heater of the type having a casing divided internally into inner and outer chambers communicating only at their lower ends, a second casing provided at the upper end of the first casing, said second casing being separable from and adjustable with respect to said first casing, the side walls of the second casing having portions inwardly offset with respect to the side walls of the first casing, and angularly related vertically disposed partition walls dividing said second casing into a pair of adjoining compartments, one of said compartments communicating with the inner chamber of said first casing and the other compartment communicating with the outer chamber, each compartment having an exterior wall formed by a portion of the walls of said second casing, an exterior wall of each compartment having an opening through which communication between the compartment and an air conductor is established.

WILLIAM S. SOMERS.
